STRESS INDICATOR FOR BOLTS OR STUDS

Albert Rivington Stone, Baltimore, Md., assignor
to Gerotor May Corporation, a corporation of
Maryland

Application November 12, 1946, Serial No. 709,202

5 Claims. (Cl. 177—311)

1

My application for patent is a continuation in part of my copending application Serial No. 588,650, filed April 16, 1945, entitled Fastening device, now Patent No. 2,413,797, dated Jan. 7, 1947, and the invention relates to bolts, studs, and the like, and more particularly concerns a method of and assembly for, indicating or signalling changes in stresses or strains in such bolts, studs or the like.

An object of my invention is to provide a mode of determining variations in stresses in bolts, studs and similar fastening devices which have already been seated into the workpiece which is at once simple, effective, inexpensive and instantaneous in operation.

Another object is to provide an assembly for determining variation in stresses encountered in bolts, studs and other fastening devices which have previously been seated in the workpiece, which are simple, effective, and rapid in operation, small sturdy and compact, of low first cost, substantially fool-proof, extremely rugged and of long useful life.

Other objects and advantages will in part be obvious and in part more fully pointed out hereinafter during the course of the following description, taken in the light of the accompanying drawings.

My invention accordingly resides in the several procedural and manipulative steps, and in the several parts, elements and features of construction and as well, in the combination of each of the same with one or more of the others, the scope of the application of all of which is more fully set forth in the claims at the end of this specification.

In the drawing, wherein I have disclosed that embodiment of my invention which I prefer at present, the single figure is a view, partly in longitudinal section, and partly schematic, showing an assembly incorporating the essential features of my invention.

As conducive to a more thorough understanding of my new practice and assembly, it may be noted that at this point, in the present, somewhat hurried era, wherein premium is placed upon optimum results in all fields of industrial, commercial and scientific practice, the tendency has veered more and more towards the use of high fluid pressures in all prime movers and generally kindred fluid and gaseous techniques. Many objectives motivate this general practice. Economy in steam engines, steam turbines, as well as turbines motivated by other fluids, internal combustion engines of all sorts, fractionating columns

and similar devices in oil and other distillation techniques, all demand units which will withstand pressures which were unknown several decades back. Economy and reduction in size is one objective. In other instances, the technique simply cannot be carried effectively to an end in the absence of high pressure techniques. Uniformity in pressure distribution is essential to prevent localized over-stressing and incipient failure at points where such over-stressing occurs.

For one reason or another, therefore, it has recently become important in all fields of high pressure practice to achieve uniform stressing and straining of bolts, studs and similar fastening devices when seated in the particular workpiece.

Once seated, these bolts and studs immediately become subject to the internal stressing from the particular fluid or other source of energy restrained within the workpiece. Such stressing, while not necessarily constant, substantially is continuous over a long term of service. Gradual enlargement of the workpiece is frequently observed. Local over-stressing may occur within the bolt or stud giving rise to a point of incipient weakness. It is important in such instances that the very outset of such failure be called to the attention of the operator. When in this manner, the operator is given sufficient warning it is quite possible that he can set in motion such precautionary steps as will rectify the situation and avoid the threatened failure. Should, however, he wait until the next routine inspection, quite possibly failure will have already occurred, or else it be too late to set in motion the required steps for correcting the situation.

While it is routine practice in many high pressure techniques to make periodic observations and measurements of pipe line, cylinder head, of whatever particular workpiece is employed, failure may possibly set in at once, intermediate such operations. If only visual or audible signals, or both, were available at the first onset of such incipient failure, preventive steps could at once be enforced and ultimate failure avoided. Considerable savings both in equipment and in loss of operation are thereby achieved.

Those actively engaged in high pressure techniques have by no means been unaware of the problems attendant upon such practice and have given considerable time and thought to these generalized objectives. To illustrate, the use of electrical strain gauges is well-recognized. For one reason or another, however, because of high first costs, complexity of construction, delicacy and fragility of instruments, amongst many other

causes, or any combination of one or more of the same, these various expedients heretofore proposed have been uniformly unsuccessful. It was not until my proposed technique appeared on the horizon that for the first time, a truly practical solution became available.

An important object of my invention, therefore, is to avoid in substantial measure the difficulties and disadvantages of the prior art and at the same time to produce an assembly and a mode of operation which gives instantaneous warning to the operator of incipient failure of bolts, studs or similar fastening devices in high-pressure systems, all at the very onset of such failure, and this in simple and reliable manner and with the use of inexpensive, simple and sturdy component parts.

In my copending application Serial No. 588,650, I disclose a self-indicating bolt, stud or other similar fastening device wherein the degree of stressing is accurately indicated, so that precisely the desired stressing, straining and length of bolt grip can be accurately achieved. Therein, essentially, I disclose a longitudinally bored bolt, stud or similar fastening device. Fast at the end of the bolt remote from the head end of the bolt, I provide a pin disposed within the bore and at all times free of stressing. This pin either projects a determined distance beyond the open head of the bolt when the latter is unstressed, or else is flush therewith when such condition maintains.

Upon stressing the bolt, the latter is elongated and moves relative to the end of the unstressed pin. The degree of movement upon proper calibration is an accurate measure of the stressing of the bolt.

My present embodiment relates to the instantaneous determination of variation in such stresses, once the bolt, stud or the like has been strained to a predetermined value. Failure due to any one of a number of causes encountered in actual practice can thus be guarded against.

In generalized terms, my invention may be considered as comprising the combination of unstressed means capable of movement relative to a stressed bolt, stud or the like, for indicating the degree of stress within the latter. This, in my present embodiment, comprises an unstressed pin fast at one end of a bore provided longitudinally within a conventional bolt or stud. A snap-switch is provided thereon to give the requisite warning. This snap-switch comprises a sensing means in the nature of an elongated rod which contacts and follows this pin in its movement relative to the stressed bolt or stud. In reality it is the bolt or stud which moves relative to the unstressed pin. This sensing means, rod-like in nature, in the present instance constitutes the plunger of a suitable micro-switch. This latter may be considered broadly as a snap mechanism which is sensitive to a change in the position of the micro-switch plunger in the order of 0.0001 inch. This corresponds to a change of stress of about 3000 pounds per square inch, per inch of bolt grip. I associate signalling means with the micro-switch plunger for signalling to the operator any change in the stressing of the bolt and the strains developed therein. Such signalling means are shown as comprising an electric circuit with a source of electric energy therein and with a signalling means, audible or visual, or both, provided therein.

From the standpoint of method of operation, my invention may be considered as comprising

stressing a bolt or stud to a predetermined point as established by a stress-indicating pin provided therein, sensing the position of the pin through a suitable micro-switch plunger, and energizing signalling means upon subsequent variation in the position of the micro-switch plunger as it follows the apparent movement of the unstressed pin relative to the stressed bolt or stud.

And now having reference more particularly to the embodiment disclosed in the single figure shown, I provide a conventional bolt, stud or the like 10, similar to that disclosed in my said application hereinbefore identified. This bolt has the usual head 11 and shank 12, and conventional threading, not shown. I provide a bore 13 longitudinally of the length of the bolt. While it is not essential that this bore extend centrally of the bolt, for simplicity, symmetry and ease in drilling, I prefer to provide such bore, along the axis of the bolt. Again while it is not essential that this bore extend completely through the bolt, it being entirely feasible for it to terminate short of the shank end thereof, I prefer, for ease of manufacture, to have it extend entirely through the bolt, and thus illustrate the same in the drawings. In the bore 13, I provide an unstressed pin 14, fast to the shank 15 of the bore, and free of the sidewalls of the latter throughout its extent. In the present embodiment during the rest conditions of the bolt, when the same is completely unstressed, the adjacent or free end of the pin 14 terminates exactly flush in nicely machined fashion, with the free or outer surface of the head 11 of the unstressed bolt.

As the bolt is seated into the workpiece, whatever the latter may be, a strain is set up by the external stressing at once to elongate the bolt and to cause an apparent retraction of the head of the unstressed pin 14A within the bore 13. The extent of the retraction of the end of the pin within the bore by proper calibration, serves as a measure of strain imposed within the bolt, and when a predetermined retraction has been observed, the operator knows that the desired stress has been exerted and can thereupon discontinue the tightening operation. Uniform stressing throughout the workpiece can be effectively achieved in rapid efficient manner.

I associate with the bolt 10 a suitable sensing mechanism to contact and follow the pin 14 in its movement relative to the bolt or stud. After the bolt has once been seated, it is obvious that upon occurrence of incipient failure at one particular point of the workpiece the bolt in that region will tend to become overstressed. This may be due to increase in internal pressure for some reason, as, to illustrate, failure of the excess pressure relief means; upon failure of the metal of the workpiece due perhaps to localized crystal failure; gas flaws or the like; or failure of the metal of the bolt, due to localized overstressing; gassy spots in the metal, or the like. Regardless of the reason for such failure, it is accompanied by localized overstressing of the bolts, studs or similar fastening devices in the general region of such failure. Increased stressing of the bolt occurs, and further apparent movement takes place between the stressed bolt or stud and the unstressed pin 14. The function of the sensing means, is to follow this pin and to indicate by relative change in position between the end of the pin and the end of the bolt 10. In the present embodiment, I employ for this purpose a micro-switch 16, of conventional design. Micro-switches of this general type are well-known to

the art and are already available on the market. An entirely suitable and adequate form of such switch is manufactured for example by the Micro-Switch Division of the First Industrial Corporation, having its main office and factory at Freeport, Ill. A discussion of the details of this switch are not per se necessary for a proper understanding of this invention.

Only that portion of the micro-switch will be disclosed which is essential for a proper understanding thereof. Such switch includes a plunger 17 which is adapted to contact with the end of pin 14 of the bolt 10 in the movements of such pin relative to the bolt proper. That is, as the bolt 10 elongates with the effect of the pin 14 retracting within the bore 13, the micro-switch plunger 17 will follow until at such time as it causes break in the allied electric circuit hereinafter to be described.

An annular sleeve 16A is provided on the switch 16, internally threaded at 16B to adapt the same for mounting on any particular bolt or stud, the elongation of which is to be determined. Inasmuch as this skirt 16A is of fixed diameter and since various size bolts are encountered in practice, and further, since it is desirable to make one size of micro-switch adaptable for all of the different sizes or bolt heads, I provide an adaptor 18 between the bolt 10 and the micro-switch 16. It is of course entirely feasible to provide a different size micro-switch 16 for each size of bolt head. The expense of manufacture in the more limited quantities, however, and as well, the increased costs of inventory to maintain the various sizes of micro-switch on hand in the particular plant greatly increases the costs of such practice as contrasted to the use of such adaptors.

The adaptor 18 cooperates with a threaded extension 11A provided on the outer face of the head 11 of the bolt 10. The bore 13 extends through this threaded extension, and the end 14A of the bolt 14 terminates flush with the outer extremity of this extension 11A when the latter is in an unstressed or rest or neutral position. The adaptor 18 is internally threaded as at 18A, in a suitable recess, to receive the threads of the elongated extension 11A of the particular bolt 10. There are as many different sizes of adaptors 18 provided as there are different sizes and contoured bolt heads 11 in use.

An elongated extension 18B is provided at the other end of the adaptor 18 externally threaded for cooperation with the threads 16B on the interior of the elongation 16A of the micro-switch 16. Regardless of the diameter of the recessed portion of the adaptor 18 the shank portion 18B thereof is of fixed diameter with threading engaging with that of the extension 16A of the micro-switch 16. In this manner the micro-switch 16 is made fast to the end of the previously-stressed bolt or stud 10. It is threaded down until the micro-switch plunger 17 is in abutting contact with the end 14A of the pin 14 within the bolt 10. At this time, a closed circuit is completed across a simple series signal circuit cooperating with the micro-switch 16. The coursing of the current through such circuit may be traced from the lower side of the switch 16 through lead 19 to battery or other suitable source of electric supply 20 indifferently alternating or direct current through lead 21 to signalling device 22. This may be a buzzer, bell or other suitable signal, or may be a warning light or the like. It is entirely within the province of my invention that both audible and visual signals be

employed. From the signalling device 22 the current courses lead 23 back to the micro-switch 16 thus completing the circuit. Should alternating current supply be employed, the coursing of the current during the next subsequent half-cycle of current flow is exactly the opposite of that just traced.

In use the bolt or stud, is tightened to the desired stressing as indicated by retraction of the free end of the unstressed pin 14 to a determined extent within the threaded extension 11A of the head 11 of the bolt 10. The micro-switch 16 is then applied to the head end of the bolt 10 until the micro-switch plunger 17 just abuts the free end 14A of the unstressed pin 14. If desired, and in the manner hereinbefore more completely described, an adaptor 18 may be provided between the threaded extension 11A of the bolt 10 and the shank portion 16A of the micro-switch 16. While this adaptor of course may be omitted, it is desirable in that it adapts a standard thread on the switch body 16 to serve different sizes of bolts or studs 10. A set screw or the like 24 serves to make the micro-switch 16 fast to the adaptor 18. As has also been pointed out hereinbefore the switch 16 is highly sensitive, indicating for example plunger 17 of the order of about 0.0001 inch. Consequently, since this distance represents a change in bolt tension of but 3000 pounds per square inch per inch of bolt grip it is evident that this new combination is highly sensitive to a very small change in the tension of the bolt. When localized failure begins either in the workpiece or in the strained bolt itself, under the tremendous operating pressures encountered, further elongation of the bolt or stud 10 occurs with consequent apparent recession of the pin 14 within the bore 13. As the plunger 17 follows such motion it closes a previously opened circuit indicated generally at 26 and energizes the signal device 22, either visual or audible.

For the first time, in rapid, simple and ingenious manner, it has been made possible for the attendant to receive preliminary warning of the prospective failure of the system. This warning becomes available to him regardless of whether he is giving immediate attention to this particular phase of his duties. This distinguishes sharply from the practice heretofore existing, wherein incipient failure could be determined only at such times as actual caliper measurements were being taken. The warning device fits on and combines readily with the standard new and improved stud or the like. Its use is particularly advantageous in inaccessible places, where the attendant is apt to be lax in his observations. Failure could readily occur between measurements and the operator be entirely unwarmed until destruction had already taken place.

It is of course, readily understood that it is entirely within the province of my invention to substitute for the working elements, a recording mechanism if desired. Or both may be employed in a typical instance.

The device is simple, efficient, rugged, and of long useful life. A minimum number of parts are employed, none of which are moving.

All these and many other thoroughly practical advantages attend upon the practice of my invention. Inasmuch as, once my invention is disclosed, many modifications and adaptations will readily occur to those skilled in the art, and since further many embodiments of the basic inventive concept will likewise suggest themselves, I intend

that the foregoing disclosure be considered merely illustrative and not by way of limitation.

I claim:

1. In combination, a bolt or stud adapted to be stressed, an unstressed pin provided in a longitudinal bore within said bolt or stud and fast at one end of the bore, means fastened to the bolt or stud adjacent the other end of said bore comprising a micro-switch having a plunger adapted to contact, follow and sense the movement of said pin relative to the bolt or stud, and an electrical indicating circuit connected to said micro-switch for indicating excessive movement of said micro-switch plunger.

2. In combination, a longitudinally bored bolt or stud adapted to be stressed, an unstressed pin within said bore and fast to the bolt or stud at one end thereof, means fastened to the other end of said bolt or stud and including a snap-switch means having a follower plunger adapted to contact and follow said pin and sense the movements thereof relative to said bolt or stud, and electrical signal means connected to said snap-switch means for signalling increased stressing of said bolt or stud upon movement of the plunger.

3. In combination, a longitudinally-bored bolt or stud adapted to be stressed, an unstressed pin within said bore and fast to the bolt or stud at one end of the said bore, said bolt or stud having a threaded portion at the other end thereof, an adapter threadedly engaging said other end of said bolt, a micro-switch threadedly engaging said adaptor and having a sensing plunger contacting and following said pin in its movement relative to said bolt or stud, and electrical signalling means connected to said micro-switch for signalling increased stressing of said bolt or stud upon predetermined movement of the micro-switch plunger.

4. In combination, a bolt or stud adapted to be stressed and having a longitudinal bore therein, a continuously unstressed pin loosely provided in said longitudinal bore and having one end

thereof fastened to the bolt or stud with the other end of the pin being free, means fastened to the bolt or stud adjacent the free end of said pin and having a sensing finger adapted to follow the free end of the pin upon stressing of the bolt or stud, and means associated with said sensing finger for indicating movement of the latter beyond a predetermined limit.

5. A system for determining strain variations in previously stressed bolts or studs, comprising in combination, a bolt or stud having a longitudinal bore therein, longitudinal means within said bore and secured at one end thereto and free at the other end permitting relative movement of said bolt or stud with respect to the free end of said longitudinal means in accordance with changes of stress suffered by the bolt or stud, means fastened to the bolt or stud and comprising means for continuously contacting the free end of said longitudinal means within the bore, and means associated with said contacting means for indicating that the relative movement has surpassed a predetermined limit of stress of the bolt or stud.
